FOLDABLE STAND

Irwin C. Bowman, Chicago, Ill.

Application October 22, 1945, Serial No. 623,780

4 Claims. (Cl. 311—80)

1

The invention relates to collapsible stands.

One object of the invention is to provide a stand which is collapsible when not in use and includes a top which is adapted for use as a tray.

Another object of the invention is to provide a collapsible stand of this type which can be fabricated of light material, such as cardboard or plywood, in quantities at a low cost.

Other objects of the invention will appear from the detailed description.

The invention consists in the several features hereinafter set forth and more particularly defined by claims at the conclusion hereof.

In the drawings:

Fig. 1 is a perspective of a stand set up for use.

Fig. 2 is a perspective of the stand partly folded, for illustrative purposes.

Fig. 3 is a section of the stand taken on line 3—3 of Fig. 2, with the parts fully collapsed.

Fig. 4 is a horizontal section taken on line 4—4 of Fig. 1.

Fig. 5 is a vertical section of the upper portion of the stand when set up for use.

Fig. 6 is a plan of the blank sheet from which the body of the stand is formed.

The invention is exemplified in a stand which comprises generally, a series of side-panels of sheet material which form a symmetrical supporting body, and have their contiguous margins foldably joined together so they may be collapsed into substantially parallel relation, a foldable inner top-panel for holding the side-panels in supporting relation, and an article-supporting top, foldably connected to the upper end of the body so it will overlie and be supported by the body when the latter is extended for use, and so it will be foldable into substantially parallel relation with the panels when the body is collapsed.

The side-panels are formed of light-weight sheet material, such, for example, as cardboard or other suitable material. When the side-panels are spread apart, they form a symmetrical body which is polygonal in horizontal cross-section, preferably hexagonal, whereby the article-supporting top 9 is firmly and horizontally supported for use. These panels include a front-panel 10, a back-panel 11, and a pair of side-panels 12 between each end of the front and back panels. These panels are foldably joined at their meeting edges as at 13 to permit the panels to be folded or collapsed into substantially parallel relation. The panels are integral and rendered foldable relatively to one another by scoring along their meeting edges.

When the stand is in its extended position for use, the side-panels function as vertically rigid legs for firmly supporting the top 9, and the leaves 14 and 15 of the inner top horizontally connect and prevent spreading of the front-panel 10 and back-panel 11 and hold all the upright panels in symmetrical relation. The stand may

2

be collapsed by swinging the top 9 into parallel relation to the back-panel 11, as top 9 is thus swung, and leaves 14 and 15 will be folded together and move panels 10, 11 and 12 together.

5 The inner top-panel includes a pair of leaves 14 and 15 which have their inner ends foldably joined at 16. The outer margin of leaf 14 is foldably joined to the back-panel 11 at 17, and the outer margin of leaf 15 is foldably joined to the front-panel 10 at 18 by a flap 20 which is secured by an adhesive to the front face of panel 10. When the body and leaves 14, 15 are extended, this inner top-panel holds oppositely disposed panels 10 and 11 against spreading, and 10 the body symmetrically extended. The supporting top 9 is secured to the upper face of leaf 14 by a suitable adhesive and is foldable with said leaf. When the body is extended, the top 9 will be supported by the connected upright panels 10, 11 and 12. When the body and leaves 14 and 15 of the top-panel are collapsed, the supporting top 9 will be in parallel relation with the side-panels 10, 11 and 12.

15 In order to provide for holding the stand against collapse, and conveniently transporting it while articles rest on the top, a hand-hole or opening 23 is formed in the front-panel 10, a thumb-hole 24 is formed in leaf 15 and a thumb-hole 25 is formed in top 9. By grasping top 9 and leaves 14, 15 of the inner top-panel between the thumb and fingers of one hand, all of the foldable parts of the entire stand may be firmly held in extended relation and against collapse, for transporting the top 9 with articles thereon until the stand is set on the floor. This provision for 20 conveniently grasping the top 9 and the inner top-panel renders means for locking the foldable elements in position. When the stand rests on the floor, top 9 and inner top-panel 14, 15 hold the 25 panels 10, 11 and 12 in symmetrical relation for supporting the top 9.

The invention contemplates forming the body, including the front-panel 10, back-panel 11, side-panels 12 and leaves 14, 15 of the inner top-panel 45 from a single piece or blank of suitable sheet material, as illustrated in Fig. 6. The sheet is scored as at 13 to form flexible joints between the front, side and back panels of the body; as at 17 to form a flexible joint between back-panel 11 and leaf 14 of the inner top-panel; as at 16 to form a flexible joint between leaves 14 and 15; and as at 18 to form a flexible joint between leaf 15 and the flap 20 which is secured to front-panel 10. The sheet is also scored as at 26 to provide a flap 27 which laps one margin of the front-panel 10 and is secured thereto by an adhesive.

In fabricating the body, the flap 27 is secured to one of the side margins of the front-panel 10 and the flap 20 is secured to the upper margin of the front-panel 10. The top 9 is also formed of suit-

able sheet material, such as cardboard or plywood.

When the stand is extended, as illustrated in Fig. 1, the supporting top 9 will be firmly supported on the body and will hold the leaves 14 and 15 of the inner top-panel against relative movement to prevent collapse of the body. When the stand is extended and to be transported, the user will insert a hand through the opening 23, and grasp the top 9 and leaves 14, 15 of the inner top-panel, through openings coincident 24 and 25.

The stand is particularly adapted for use as a small table or support for serving refreshments, and for that purpose is light in weight. Preferably, the upper face of the top 9 is provided with a suitable finish to render it resistant to liquids and readily cleanable.

When the stand is not in use, it may be collapsed so that the body and top 9 will be in substantially parallel relation. A large number may be stacked in a small space or, if desired, may be hung on hooks which are adapted to extend through the thumb-hole 25 in the top 9.

The invention exemplifies a suitable stand of the character described which may be advantageously used in serving foods or liquid refreshments, which is foldable for convenient storage, can be produced at a low cost, readily extended and foldable, and which is provided with simple means for grasping the stand and holding it against collapse when transporting articles thereon.

The invention is not to be understood as restricted to the details set forth, since these may be modified within the scope of the appended claims without departing from the spirit and scope of the invention.

Having thus described the invention, what I claim as new and desire to secure by Letters Patent is:

1. A collapsible stand adapted to be transported by one hand and comprising a continuous series of flat upright side-panels formed of sheet material and having the contiguous side margins thereof foldably connected together in order that they may be collapsed into substantially parallel relation and spread laterally to form a self-sustaining vertical body, a top-panel including a pair of foldably joined leaves extending between, and foldably joined to, the upper ends of two opposite side-panels, and a flat article-supporting top fixedly secured on one of the leaves, adapted to overlie and project from the side-panels when they are spread apart and to rest on the top-panel, and foldable into substantially parallel relation with the side-panels and the leaves when the body and leaves are collapsed, one of the side panels and one of the leaves and the top being provided with means whereby the top and top-panel may be grasped and pressed together by one hand to prevent folding together of the leaves and collapse of the body when the stand is being transported.

2. A collapsible stand adapted to be transported by one hand and comprising a continuous series of upright flat side-panels formed of sheet material and having the contiguous side-margins thereof foldably connected together in order that they may be collapsed into substantially parallel relation and spread to form a self-sustaining vertical body, a top-panel including a pair of foldably joined leaves extending between, and foldably joined to, the upper ends of two opposed side-

panels, and a flat article-supporting top fixedly secured on one of the leaves, adapted to overlie and project from the side-panels when they are spread apart and to rest on the top panel, and foldable into substantially parallel relation with the side-panels and the leaves when the body and leaves are collapsed, one of the side-panels and one of the leaves and the top being provided with openings whereby the top and top-panel may be grasped and pressed together by one hand to prevent folding of the leaves and collapse of the body when the stand is being transported.

3. A collapsible stand adapted to be carried by one hand and comprising a continuous series of six upright flat side-panels formed of sheet material and having the contiguous side-margins thereof foldably connected together so that they may be collapsed into substantially parallel relation and spread to form a self-sustaining vertical hexagonal body, a top-panel including a pair of foldably joined leaves extending between, and foldably joined to, the upper ends of two opposed side panels, and a flat article-supporting top fixedly secured on one of the leaves, adapted to overlie and project from the side-panels when they are spread apart and to rest by gravity on the top-panel, and foldable into substantially parallel relation with the side-panels and the leaves when the body and leaves are collapsed, one of the side-panels and one of the leaves and the top being provided with means whereby the top and top-panel may be grasped and pressed together by one hand to prevent folding of the leaves and collapse of the body when the stand is being transported.

4. A collapsible stand adapted to be carried by one hand and comprising a continuous series of six flat upright side-panels formed of sheet material and having their contiguous side-margins foldably connected together so that they may be collapsed into substantially parallel relation and spread to form a self-sustaining vertical hexagonal body, a top-panel including a pair of foldably joined leaves extending between, and foldably joined to, the upper ends of two oppositely disposed side-panels, and a flat article-supporting top fixedly secured on one of the leaves, adapted to overlie and project from the side-panels when they are spread apart and to rest on the top-panel, and foldable into substantially parallel relation with the side-panels and the leaves when the body and leaves are collapsed, one of the side-panels being provided with a hand opening and one of the leaves and the top being provided with finger openings whereby the top and top-panel may be grasped and pressed together by one hand to prevent folding together of the leaves and collapse of the body when the stand is being transported.
